CLAIM

The ornamental design for a pinball machine, as shown and described.

DESCRIPTION

FIG. 1 is a top perspective view of a pinball machine showing our new design;

FIG. 2 is a side elevational view thereof, the side opposite that shown in FIG. 2 being almost the mirror image of FIG. 2;

FIG. 3 is a front end elevational view thereof;

FIG. 4 is a rear end elevational view thereof; and

FIG. 5 is a top plan view thereof.

FIG. 1

FIG. 5

FIG. 2

FIG. 3

FIG. 4
